UNITED STATES PATENT OFFICE.

CHRISTIAN REISS AND WILLIAM G. BRADBURY, OF NEW YORK, N. Y.

CURTAIN-FIXTURE.

SPECIFICATION forming part of Letters Patent No. 758,216, dated April 26, 1904.

Application filed April 10, 1903. Serial No. 152,081. (No model.)

To all whom it may concern:

Be it known that we, CHRISTIAN REISS and WILLIAM G. BRADBURY, of 35 Inwood avenue, Highbridge, New York city, New York county, New York State, have invented a new and Improved Curtain-Fixture, of which the following is a full, clear, and exact description.

The invention relates to supports for shade-rollers, curtains, &c.; and its object is to provide a new and improved curtain-fixture which is simple and durable in construction and arranged for convenient attachment to the window or door frame or other article to securely hold or support the shade or curtain roller in place.

The invention consists of one piece of sheet metal bent and twisted in such a way as to be able to attach it to the window or door frame with ease and without any damage to the front woodwork whatever, as will be hereinafter described and then pointed out in the claim.

Reference is to be had to the accompanying drawings, forming part of this specification, in which similar letters of reference indicate corresponding parts in all the figures.

Figure 1 is a perspective view of the improvement as applied. Fig. 2 is a piece of sheet metal being punched and ready to be bent and twisted into the improvement. Fig. 3 is a view of the fixture ready for attachment.

The improved curtain-fixture, as illustrated in Fig. 1, is made of sheet metal, and the special device shown is provided with bodies P P', formed at their upper ends with widened offsets G, which have downwardly-extending

teeth B, formed by stamping down portions of the offsets, adapted to be driven into the top of the window-frame, door-frame, or other support. The bodies P P' rest throughout their length on the front face of the support H, and at the lower ends of said bodies are forwardly-extending portions D, formed with a half-twist, as at E, which carry keepers F, adapted to support the ends of the shade or curtain roller I, as plainly illustrated in Fig. 1.

It will be seen that the entire curtain-fixture can be readily attached to the window-frame, door-frame, or other support H by simply driving the teeth B into the top of the edge of the said support, so that the bodies P P' rest flush on the front face of the support.

Having thus fully described our invention, we claim as new and desire to secure by Letters Patent—

A curtain-fixture provided with a body adapted to rest on the face of the support the upper end of said body being formed with a widened offset, two downwardly-extending teeth or spurs punched out of the widened offset, and a forwardly-extending projection at the lower end of the curtain-fixture with a bend and a half-twist carrying a keeper, substantially as shown and described.

In testimony whereof we have signed our names to this specification in the presence of two subscribing witnesses.

CHRISTIAN REISS.
WM. G. BRADBURY.
